UNITED STATES PATENT OFFICE.

ARTHUR W. CASH, OF NEWARK, NEW JERSEY, ASSIGNOR TO THE FOSTER ENGINEERING COMPANY, OF SAME PLACE.

FLUID-PRESSURE-CONTROLLED GOVERNOR.

SPECIFICATION forming part of Letters Patent No. 591,815, dated October 19, 1897.

Application filed June 5, 1897. Serial No. 639,508. (No model.)

To all whom it may concern:

Be it known that I, ARTHUR W. CASH, a citizen of the United States, residing at Newark, in the county of Essex and State of New Jersey, have invented new and useful Improvements in Fluid-Pressure-Controlled Governors, of which the following is a specification.

This invention relates to a fluid-pressure-controlled governor, and comprises a rotary force-pump actuated from the engine or pump to be governed, a main casing or chamber enclosing the rotary pump and having a pipe connecting with a suitably-arranged throttle-valve to be automatically operated by the varying fluid-pressure in said pipe and main casing, and a second casing or receptacle attached to and connected with the main casing and adapted, primarily, as a reservoir for the oil or other fluid to be fed to the main casing through a free passage and also to receive back from the main casing any surplus fluid through an opening capable of being restricted by adjustment of a valve or screw-plug to so regulate the pressure in the main casing or chamber that when the speed of the engine or pump is abnormally increased the fluid-pressure in the said main casing and its pipe connection to the throttle-valve is also increased, thereby tending to close the throttle, and when the speed of the engine or pump is decreased the fluid-pressure in the main casing and pipe to throttle is decreased to permit a further opening of the throttle.

It is the special purpose of my improvements to simplify and cheapen the construction of a rotary fluid-pressure-controlled speed-governor for engines and pumps and to provide for reliable automatic action to accord with varying requirements of the engine or pump to be regulated.

My invention consists in the novel features of a rotary fluid-pressure-controlled governor, as hereinafter set forth.

In the annexed drawings, Figure 1 is a sectional elevation of my improved speed-governor, the oil-reservoir and plate that separates said reservoir from the main chamber being removed. Fig. 2 shows a modification of the throttle-valve in part sectional elevation. Fig. 3 is a top view of the reservoir

for fluid and the casing that incloses the rotary force-pump of the governor, with connections to a moving part of the engine or pump to be governed. Fig. 4 is a vertical transverse section of the governor, with connections to engine.

The main casing 1 of the governor, Figs. 1, 3, and 4, is adapted to be secured rigidly to a bracket on the steam-chest, or some other suitable portion of the engine or pump-frame, by means of screws at 22, or elsewhere. In the lower portion of this main casing or chamber 1, as shown in Fig. 1, there is an approximately elliptical space or recess 3, formed by segmental overhanging abutments 4, that project into the said casing from the walls thereof. Within this recess 3 are fitted two intermeshing hollow gears or pinions 5, that are adapted and arranged to constitute a rotary force-pump for elevating a liquid, such as oil, to the upper chamber 6 of the main casing.

To provide an oil-reservoir for the main casing 1, there is secured to one side of said main casing a second casing, cap, or chamber 7 and an intervening partition-plate 8, Fig. 4, by means of suitable screws 99, passing through the cap 7 and plate 8 and threaded into the walls of the main casing. At its top the chamber or reservoir 7 is provided with a filling-orifice 10, which is preferably threaded, to be closed by a plug or valve. In the partition-plate 8, at the bottom of the oil-reservoir 7, is a feed-opening 11, Fig. 4, leading into the lower central part of the recess 3, in which the gears 5 are fitted, the feed of fluid into the main casing being thus on the lower side of and between the said gears that constitute the rotary pump. For the return of fluid to the reservoir 7 there is provided in the plate or partition 8 an upper opening 12, Fig. 4, controlled by a movable screw-plug 13, that is supported in a tubular boss 14 on the outer wall of the reservoir.

An upper portion of the main casing 1 is provided with a bearing 15, Figs. 3 and 4, in which is mounted a rock-shaft 16, having a rocker arm or lever 17 attached to its outer end. The inner end of this rock-shaft 16 is formed with or carries two arms 18 at nearly right angles to each other. These arms 18 occupy dependent positions, as shown in Fig.

1, and carry at their extremities spring-pressed pawls 19, which engage alternately with the teeth of the two hollow gears or pinions 5 and drive them forward to the extent 5 of two teeth for each oscillation of the rock-shaft in either direction. The pawls 19 are pivoted to bifurcated ends of the rock-shaft arms 18, which are cored to receive blocks 20, Fig. 1, that bear against the pawls under 10 the pressure of springs 21 at the back of said blocks, so that the said pawls will engage the gears 5 with elastic pressure.

The rocker arm or lever 17, on the outer end of the rock-shaft 16, connects by a link 15 22 with a piston-rod 23 or other reciprocating part of a steam pump or engine. Assuming that the length of stroke for the piston-rod 23 is from the point 24 to the point 25, Fig. 1, and that the piston is in the center of 20 its stroke, then when the end of the link 22 has moved to the point 24 or 25 the rocker arm or lever 17 will have traveled the distance indicated between points 26 and 27, and this movement, transmitted through the 25 rock-shaft 16 and pawls 19, will have advanced the gears 5 forward two teeth on each gear or eight teeth on both gears for one complete stroke of the said pump or engine piston.

30 From the top of the main governor-casing 1 there is extended a vertical pipe 28, connecting with a centrally-perforated screw-plug 29, Figs. 1 and 2, in the end of a cylinder 30, that is fitted with a plunger 31 for actuating a balanced throttle-valve 32, that is inclosed in a valve-casing 33, which is mounted on the cylinder 30 and adapted to communicate with the steam-supply for the pump or engine to be governed.

40 In the construction shown in Fig. 1 the fluid-pressure in the pipe 28 is arranged to act against the opposing pressure of a spring 34, inclosed in the plunger 31 and surrounding the plunger-stem 35, which is arranged 45 to bear against the stem of the balanced throttle-valve 32 on increase of pressure in the pipe 28, and thereby move the throttle-valve to a closed or closing position.

If desired, there may be employed in connection 50 with the throttling device a pressure-regulator of the character shown and described in United States Patent No. 354,951, in which the movement of the valve 32, controlling the pressure-supply, is itself controlled by the delivery-pressure of the fluid 55 acting through port or ports 36, Fig. 1, upon a piston or diaphragm 37, attached to stem 38 of the throttle-valve, and against the action of a spring 39 or a weight.

60 In the arrangement of throttle-valve shown in Fig. 2 the steam-pressure acting on the valve tends to open the valve against the fluid-pressure acting on the lower end of the plunger.

65 With both forms of throttling device a pipe 40, Figs. 1 and 2, is provided for return to the oil or fluid reservoir 7 of any slight quan-

tity of pressure fluid that may have passed the plunger 31 in the operation of the governor.

The oil or other liquid in the reservoir 7 is free to flow through the opening 11, Fig. 4, into the space 3, Fig. 1, on the lower side of and between the gears 5 in the main casing. If now the rock-shaft 16 is caused to oscillate, 75 as by means of a lever 17, actuated from piston-rod 23, the pawls 19 will have imparted to them a movement indicated by the dotted lines in Fig. 1. Thus the gears 5 will be caused to revolve in the direction of the arrows and 80 the oil between the gear-teeth, supplied at the center of the space or recess 3 between the lower parts of the gears, will be gradually advanced along the curved abutments 4 and be delivered into the larger chamber 6 of the 85 main casing, and thence, through pipe 28, to the plunger 31 for actuating the throttle-valve. The surplus of oil or other liquid in the chamber 6 and pipe 28 will escape through the regulated opening 12, Fig. 4, past the adjusting screw-plug 13 and enter again the reservoir 7, thence to be pumped over again as the gears 5 continue to revolve.

When the speed of the steam pump or engine is increased and thereby the speed of 95 the gears 5 is also increased, the oil or other fluid will be forced into chamber 6 and pipe 28 faster than it can escape through the regulated opening 12. Consequently the pressure in the chamber 6 and pipe 28 will reach 100 such a point as to drive the piston 31 forward and close or partially close the balanced throttle-valve. On the other hand, when the steam pump or engine is running too slow 105 the pressure in chamber 6 of the governor-casing will be decreased, the plunger 31 will recede, and the balanced throttle-valve will open proportionately to the decrease of pressure in the governor.

What I claim as my invention is—
 1. A governor comprising a main casing or chamber, a force-pump located in said chamber, a rock-shaft actuated from a reciprocating part of the pump or engine to be governed and carrying pawls engaging with said force-pump, a reservoir for fluid-pressure communicating with the main casing or chamber of the governor through a free feed-passage and also through an adjustably-restricted return-passage, a cylinder communicating with the main casing or chamber of the governor and provided with a piston or plunger, and a throttle-valve directly actuated from said plunger to control the pressure-supply for the pump or engine governed, substantially as 115 described.

2. A governor comprising a main casing or chamber, a force-pump composed of intermeshing gears located in said chamber, a rock-shaft actuated from a moving part of the engine or machine to be governed, mechanism carried by said rock-shaft to engage and drive the pump-gears, a reservoir communicating with the main casing or chamber 130

- through a feed-passage for supply of fluid to the pump and also through a return-passage, a cylinder communicating with the main casing or chamber of the governor and provided 5 with a piston or plunger, and a throttle-valve actuated from said plunger to control the pressure-supply for the engine, pump, or machine to be governed, substantially as described.
- 10 3. A governor comprising a main casing or chamber, a force-pump consisting of intermeshing gears mounted in said chamber, a rock-shaft provided with pawls for driving said gears, means for actuating said rock-shaft from a moving part of the pump or engine to be governed, a reservoir for fluid-pressure communicating with the main casing or chamber of the governor through a free feed-passage and also through an adjustably-restricted return-passage, and a cylinder communicating with the main casing or chamber of the governor and provided with a plunger for actuating a throttle-valve, substantially as described.
- 15 4. A governor comprising a main casing having an approximately elliptical recess therein and a larger chamber communicating with said recess, a force-pump consisting of two intermeshing gears fitted in said elliptical recess, a rock-shaft having arms provided with pawls engaged alternately with the teeth of said gears, means for connecting said rock-shaft with a moving part of the pump or engine to be governed, a reservoir 20 for fluid-pressure communicating with a space below and between the gears through a free feed-passage and also communicating with the larger chamber of the main casing through an adjustably-restricted return-passage, and 25 a pipe through which the said larger chamber of the said main casing communicates

with a cylinder having therein a plunger for actuating a throttle-valve to control the pressure-supply for the pump or engine governed, substantially as described.

45

5. A governor having a main casing inclosing an approximately elliptical recess and a larger chamber communicating therewith, two intermeshing rotary gears fitted in said recess and constituting a rotary pump for 50 forcing pressure liquid into the larger chamber of said casing, a rock-shaft having arms provided with spring-pressed pawls alternately engaging the teeth of said gears, means for actuating said rock-shaft, pawls and gears 55 from a moving part of the engine or pump to be governed, a reservoir for fluid-pressure communicating with the main casing, a pipe leading from said main casing to a cylinder having a plunger for actuating a throttle- 60 valve by fluid-pressure, and a pipe leading from said cylinder for return of oil or liquid to the reservoir, substantially as described.

60

6. A governor comprising a casing having therein an approximately elliptical recess, 65 two intermeshing rotary gears fitted in said recess to force oil or liquid upward in said casing, a pipe through which said casing communicates with a cylinder having a plunger to actuate a throttle-valve, a rock-shaft having arms provided with pawls to drive the said gears, an arm or lever on said rock-shaft, and a link connecting said rock-shaft lever with the piston-rod of an engine or pump, 70 substantially as described.

75

In testimony whereof I have hereunto set my hand in presence of two subscribing witnesses.
